CLAIM

The ornamental design for a display screen or portion thereof with animated graphical user interface, as shown and described.

DESCRIPTION

FIG. 1 shows a first image in a sequence for a display screen or portion thereof with animated graphical user interface showing our new design;

FIG. 2 shows a second image thereof;

FIG. 3 shows a third image thereof;

FIG. 4 shows a fourth image thereof; and,

FIG. 5 shows a fifth image thereof.

The appearance of the animated user interface sequentially transitions between the images shown in FIGS. 1-5. The animated user interface may sequentially transition between the images shown in order from FIG. 1 to FIG. 5 or from FIG. 5 to FIG. 1. The process or period in which one image transitions to another image forms no part of the claimed design.

The broken lines showing a mobile device and portions of the graphical user interface form no part of the claimed design.
